UNITED STATES PATENT OFFICE

ARTHUR M. KIRKWOOD, OF PORTLAND, OREGON, ASSIGNOR, BY DIRECT AND MESNE ASSIGNMENTS, TO LOG DEBARKING AND SIZING CORPORATION

DEBARKING MACHINE

Application filed May 2, 1929. Serial No. 359,833.

My invention relates to debarking machines used in the manufacture of lumber, paper pulp and the like.

Heretofore, in log debarking machines the logs which are to have their bark removed have been brought up to the machine on conveyer chains or the like and held in contact with the debarking means on movable carriages or similar elaborate machinery, all of which is expensive, as to initial cost, upkeep and operation.

The object of my invention is to provide a log debarking machine adapted to be located on a float or adjacent to a body of water, and to provide in combination with the debarking means, means for grasping and holding a log, while in the water, in contact with the debarking means of the machine. The advantages of such arrangement are: The log may thus be conveniently and economically conveyed to the machine by floating on the surface of the water, as in a mill pond; and, due to its relatively lighter weight while in the water is more easily handled; and finally the log may be economically disposed of after it has been operated on, by merely floating it away.

In this connection it may be said that the most economical and favored transportation, and storage of logs is by water, and thus by providing a machine adapted to debark a log without the necessity of removing it from the storage pond, a considerable saving in time and machinery is effected.

A further object of my invention is to provide simple, but effective means for grasping and holding the log while in the water, such means further adapted to rotate the log so that the debarking means may operate on the entire circumference of the log; and the portion of the machine carrying the debarking means so arranged that the same may be moved longitudinally along the log, to apply the debarking means thereto along its entire length.

I attain these objects in a log debarking machine comprising a floatable support, spaced inclined log carrying arms hinged on said support and adjustable to variable angles with the horizontal, power means for effecting said

adjustment, a driven, traveling way provided on said arms, respectively, comprising transverse journaled shafts, sprockets, a motor and a driving connection therefrom to said sprockets, and an abutment on said way for holding said log in position on said way, whereby the travel of the way causes the log to revolve against the said abutment, the latter being adapted to move with and thus facilitate the revolving of the log.

A further object of my invention is to provide in combination with such log carrying means, debarking means adapted to remove the bark from the log in close spirals, as the log is rotated, the debarking means including a rotary cutter head carrying knives arranged transversely across the face of the cutter head at approximately an angle of 45 degrees to its axis, and curved to conform to the cylindrical face of the cutter head, so that the cutting edge of the knife will only be in contact with the log, at the point of contact of the circumferences of the cutter head and the log, whereby diagonal shearing or draw-cut is accomplished which will cut the bark off cleanly and remove and throw the bark backwards and in that way clearing the knives of the cutter head.

The above described and other incidental features of my invention, the details of construction, and the mode of operation are hereinafter described with reference to the accompanying drawings.

In the drawings:

Fig. 1 shows a side elevation of my debarking machine adapted for being mounted on a float and illustrates a log held in position in contact with the debarking machine;

Fig. 2 shows a front elevation of the same;

Figs. 3 and 4 show details of the log carrying means removed from the machine;

Figs. 5 and 6 shows details of the rotary cutter head and depth guide therefor;

Fig. 7 shows in a side elevation a modification of my debarking machine as adapted to be arranged over a flume or the like;

Fig. 8 shows a front view of the same;

Fig. 9 shows in a fragmentary view a further modification of the log carrying means of my invention;

Fig. 10 shows a section taken on the line 10—10 of Fig. 9; and

Fig. 11 shows a section taken on the line 11—11 of Fig. 9.

5 Referring now to Figs. 1 to 6 inclusive, I have shown one embodiment of my debarking machine adapted to be mounted on a raft or float *a* by which the log carrying means are carried and to hold and rotate the 10 log in the water close to and parallel with one edge of the float, so that a carriage *b* carrying the debarking means and hereinafter described, may be adapted to operate on the log.

15 The log carrying means comprise two or more arms or cradles 2, see Figs. 3 and 4, pivoted on stub shafts 3 which are journaled in brackets 4 secured to the underside of the float and beneath the surface of the water.

20 The stub shafts 3 are provided with sprockets 5 connected by chains 6 with correspondingly spaced sprockets 5a carried by a driven shaft 7 arranged parallel to the edge of the raft. A driving gear 8 is carried by the said 25 shaft 7 and connected by a chain 9 with a prime mover 10, preferably an electric motor, conveniently arranged on the raft. Another sprocket 11 is mounted fast on the stub shafts 3 and connected by a chain 12 with a 30 sprocket 14 which is fast on a shaft 15 journaled in the said arm and projecting through a longitudinal slot 2a in the arm 2.

A sprocket 16 is mounted fast on the said shaft in the slot 2a and a log rolling chain or 35 movable way 17 is mounted over the sprocket 16 and over a sprocket 20 journaled on a shaft in the outer bifurcated end 2b of the arm 2.

Upwardly projecting members 21 are secured to the outer sides of the arms 2 adjacent 40 each side of the slot 2a; in which is journaled an idling roller 23, arranged between the said members, a portion of the circumference of which is inclosed by the slot 2a. The upper end of the members 21 is connected by a flexible cable 24 passed over an idling roller 25 on the raft and connected to suitable fluid operated jacks 26.

The carriage *b* by which the debarking means are carried, is mounted adjacent the 50 edge of the float *a* and adapted to overhang the log carrying means and is movable longitudinally of the log held by the latter, being mounted on wheels *c*, riding on tracks *d* and driven by a motor *b'* through gears *e* and a 55 chain and sprocket *f*.

The carriage *b* comprises two spaced parallel frame members *b2* overhanging the water and transverse of the log carrying means on the upper cross pieces *b3* of which a pendent 60 A-frame *k* is supported, by means of short racks 30 meshing with pinions 31 carried on a transverse shaft 32 journaled on the said upper cross members. The shaft 32 is rotatable by means of a sprocket wheel 33 on 65 one end, which is connected by a chain 34 with

a sprocket 35 fast on the shaft of a crank lever 36. By these means the frame *k* is adjustable vertically. A dog 37 bearing in the teeth of the sprocket 35 holds the frame *k* from independent downward movement and a guide member 38 carried by the upper end of the frame *k*, holds it from displacement from the pinions 31.

On the lower end of the frame *k* is journaled a transverse shaft 1, see Figs. 5 and 6, carrying a rotary cutter head *p*, provided with a number of equally spaced, circumferentially disposed knives *z* curved to conform with the circumference of the cutter head and arranged at an oblique angle with its axis of rotation. A gauge wheel *q* and a driven pulley *r* are also mounted on the shaft *l*, the latter connected by a belt *s* with an electric motor *t* which is supported on a transverse member *k'* of the frame *k*. The gauge wheel *q* is mounted on the shaft *l* over an eccentric sleeve *u* which is provided with a sprocket *v* concentric with the axis of the shaft *l* and connected by a chain *w* with a sprocket 40 carried on a shaft 40a journaled on the frame *k*. The sprocket 40 is connected by a rod 32' pivoted eccentrically to its outer side to a lever 32a adjacent the operator's platform 18.

By this construction, the movement of the lever 32a rotates the sleeve *u* which being eccentric moves the roller *q* relatively to the cutter head *p* and acts as an adjustable guide to control the depth of the cut of the cutter head *p*.

A lever 41 fulcrumed on the platform 18 is connected by a rod 42 to the frame *k* and is provided for swinging the said frame through its arc to bring the rotary cutter head into and out of contact with the log.

The operation of my machine is as follows: 105 A log *y* is floated up to the raft and positioned so as to be over the arms 2 which are then elevated by means of the cables 24 and the jacks 26 to lift the log slightly so as to be supported on the arms 2, though still in the water. In this position the arms 2 will slope somewhat inwardly so that the log will rest against the idling rollers 23, and the log rolling chains 17 being driven by the motor 10 through the shaft 7 and chains 6, 9 and 12 110 rotate the log in an anti-clockwise direction.

Simultaneously the carriage *b* is positioned on the float *a* at one end of the log and the frame *k* is swung by the lever 41 until the cutter head *p* is in contact with the log, the roller *q* being operated by the operator from the platform 18 to adjust the depth of cut of the cutter head to the thickness and character of the bark. Thus, as the log is rotated the cutter head *p* will cut close spirals of bark 115 from the log as the carriage *b* is moved longitudinally of the former.

To discharge the log when it is completely debarked the arms 2 only need to be lowered and the log floated away.

Referring now to Figs. 7 and 8, I have shown a modification of my debarking machine in that the carriage is adapted to be mounted over and supported on each side of a flume, canal or the like, and the log holding means are carried by the side of the said flume.

In this modification the log is carried up to the debarking machine by the current of the flume and the log carrying means are operated to grasp and hold the log while it is being debarked. After the log has been operated on, it is released from the log carrying means and permitted to float on down the flume, to the storage pond or the like. An advantage of this embodiment of my invention is that the refuse bark may also be carried away by the flume.

The log holding means in this modification of my invention are similar to those previously described and comprise arms 50 pivoted on an elongated shaft 50a journaled in brackets 51 carried by the side wall 52 of the flume and rotated by means of a sprocket 50b and a chain 50c, arranged over a driven sprocket 53 journaled as at 52a and connected with a motor 54 by a sprocket 55 and a chain 56. The shaft 50a is provided with sprockets 57 adjacent each arm 50 over which the driving chain 57a of the arm 50 by which the log rolling chains or movable ways 58 are driven.

A clutching mechanism 59 is provided on the shaft 50a operated by a lever 60 pivoted at 60a to the side of the flume and bent at its upper end to be in convenient reach of the operator of the jacks 61 by which the arms 50 are lifted.

The carriage 70 is adapted to be mounted on each side of the flume for longitudinal movement thereof, on tracks 61a and the A-frame 62 is pivotally suspended from its upper cross pieces as at 62a.

The rotary cutter head 63, depth guiding roller 64 and driving pulley 65 are mounted on a transverse shaft 66 journaled in the lower end of the frame, so as to hang normally in contact with the log.

A belt 65a connects the driving pulley 65 with an electric motor 65b carried on the upper portion of the frame 62. A lever 67 is pivoted on the operator's platform 62b and connected by a link 67a with the sprocket 68 by which the depth guiding roller 64 is operated by a chain 64a, engaging a sprocket 64b on the depth guiding roller. A lever 69 is also similarly provided connected by a link 69a with the frame 62, for swinging the frame into and out of contact with the log.

Referring now to Figs. 9, 10 and 11: The log carrying means are slightly modified and comprise arms or cradles 80 pivotally mounted on stub shafts 81 carried by and journaled in brackets 4a secured to the underside of the float a'.

Upwardly projecting members 82 are se-

cured to each side of the arms 80 adjacent their middle points and are connected by a cable 83 passed over bearing rollers 83a carried by the float. The other end of the cables 83 is connected to suitable elevating means, as before described, whereby the arms 80 may be raised and lowered to hold or discharge a log as the case may be.

A pair of sprockets 84 are mounted fast on the stub shafts 81 and are connected by chains 85, passed over one of the said sprockets 84 as may be desirable, to a driven shaft 85a carried on the float. Another sprocket 87 is mounted fast on the stub shaft 81 and a sprocket 87a is mounted on a stub shaft 87b on the other end of the arm 80. A log rolling chain or way 88 is arranged over the said sprockets 87, 87a. A sprocket 89 is journaled on a shaft 89a in a recess provided in the arm 80 between the members 82 which meshes with the chain 88 and is driven thereby. The shaft 89a also carries a sprocket 89b. A chain 90 is arranged over the sprocket 89b and over a sprocket 91 carried between the upper portions of the members 82 and on a stub shaft 91a so arranged that a log x carried by the arm 80 will be rotated by the chain 88 and will bear against the chain 90, which also being driven will assist in rotating the log.

A further advantage of this modification is its simplified structure in that only one chain is carried by the arm 80, and the chain 90 provides a somewhat more flexible rolling abutment than the rollers 23, see Figs. 1 and 7, whereby a knot or protrusion on the log, on striking the chain 90, will merely press the chain inward, it being made more or less slack for this purpose, and thus will not displace the log from the cutter head and leave a section of bark uncut from the log.

I claim:

1. In a log debarking machine, in combination with bark removing means of the character described, a support, spaced inclined log carrying arms hinged on said support, means connected with said arms and adapted to adjust the latter at varying angles with the horizontal, a driven traveling way provided on said arms, respectively, rotatable abutments carried by said arms adjacent said traveling ways, whereby the travel of the way causes the log to revolve against said rotatable abutments and thus facilitate the revolving of the log.

2. In a log debarking machine, in combination with bark removing means of the character described, a support, spaced inclined log carrying arms hinged on said support, means connected with said arms and adapted to adjust the latter at varying angles with the horizontal, a driven traveling way provided on said arms, respectively, idling rollers carried by said arms adjacent said traveling ways, whereby the travel of the way causes

the log to revolve against said roller and thus facilitate the revolving of the log.

3. A log debarking machine comprising a floating frame, log debarking means carried by the frame, log positioning and rotating means carried by the frame and designed to engage with a floating log and to partially support the log in order to steady it with respect to the debarking means.

10 4. A log debarking machine comprising a floating frame, log debarking means carried by the frame, log positioning and rotating means carried by the frame and designed to engage with a floating log and to partially support the log in order to steady it with respect to the debarking means, and means for advancing the debarking means in the direction of the length of the log.

20 5. A log debarking machine comprising a cutter, submerged arms carried by the machine and designed to pass underneath a floating log, the log being moved transversely when fed onto the arms, means for raising the arms for partially supporting the log, and 25 for bringing it into contact with the cutter, and means for rotating the log.

30 6. A log debarking machine comprising a cutter, submerged arms carried by the machine and designed to pass underneath a floating log, the log being moved transversely when fed onto the arms, means for raising the arms for partially supporting the log, and for bringing it into contact with the cutter, and means for rotating the log and 35 means for advancing the cutter along the length of the log.

40 7. A log debarking machine comprising a floating frame, a cutter swingably carried by the frame, submerged arms carried by the frame for receiving a floating log, the log being moved transversely when floated onto the arms, means for raising the arms at an angle for positioning the log with respect to the cutter and for partially supporting 45 the log, the cutter being held against the log by gravity.

50 8. A log debarking machine comprising a floating frame, a cutter swingably carried by the frame, submerged arms carried by the frame for receiving a floating log, the log being moved transversely when floated onto the arms, means for raising the arms at an angle for positioning the log with respect to the cutter and for partially supporting 55 the log, the cutter being held against the log by gravity, means for rotating the log, and means for advancing the cutter along the length of the log.

60 9. A log debarking machine comprising a frame, a cutter carrying carriage movable thereover, a cutter swingably carried by the carriage, trough-shaped means carried by the frame and designed to pass beneath a floating log, the log being moved transversely 65 when floated onto said means, means for rais-

ing the trough-shaped means for positioning the log with respect to the cutter and for partially supporting the log, means for rotating the log in the trough-shaped means, and means for moving the carriage for advancing the cutter along the length of the log.

70 10. In a log debarking machine, an arm having an abutment forming a trough with the extremity thereof, means for hinging the arm below the surface of a body of water and means for lowering and raising the arm for allowing a floating log to be floated into the trough and to be raised thereby.
